Primary Examiner — Kevin Rudzinski(74) *Attorney, Agent, or Firm* — Nelson Mullins Riley & Scarborough, LLP(57) **CLAIM**

The ornamental design of a lamp, substantially as shown and described.

DESCRIPTION

FIG. 1 is a perspective view of a lamp embodying the design of the present invention.

FIG. 2 is a front side elevational view of the lamp illustrated in FIG. 1.

FIG. 3 is a back side elevational view of the lamp illustrated in FIG. 1.

FIG. 4 is a right side elevational view of the lamp illustrated in FIG. 1.

FIG. 5 is a left side elevational view of the lamp illustrated in FIG. 1.

FIG. 6 is a top view of the lamp illustrated in FIG. 1; and, FIG. 7 is a bottom view of the lamp illustrated in FIG. 1. The portions shown in broken lines form no part of the claimed design.

1 Claim, 7 Drawing Sheets# US D716,994 S
